PLUG FOR INGOT MOLDS

Howard K. Rigdon, Painesville, Ohio, assignor to
Hill Burgwin, Pittsburgh, Pa., as trustee

Application October 3, 1939, Serial No. 297,719

3 Claims. (Cl. 22—148)

This invention is an improved plug for the downwardly convergent bottom openings of ingot molds of the big-end-up variety commonly used for casting steel ingots.

5 Inasmuch as a plug is ordinarily good for only one pouring, cheapness is the greatest desideratum aside from the effectiveness of the plug in serving its intended purpose. Heretofore, relatively inexpensive plugs of refractory material 10 have been used, but these have proven to be unsatisfactory because of breakage, and more particularly because particles of the material, or gas bubbles resulting from contact of the molten metal with the material, frequently rise into the 15 body of molten metal during the teeming of the ingot resulting in so-called "inclusions" in the ingot, and blow-holes or weak spots in the steel plates or strips subsequently rolled therefrom. Solid cast iron plugs are free from the above objections, but are expensive. Attempts have been 20 made to retain the virtue of the cast iron plug and reduce the cost by applying a stamped or sheared metal plate to the top of a body of refractory material and securing it thereto by a bolt or similar means, thereby to produce a composite 25 plug which fits entirely within and closes the bottom opening of the mold. Such a plug, provided the stamped or sheared plate is free from burrs, gives very satisfactory results, but by reason of its construction is relatively expensive.

The general purpose of my invention is to produce a plug composed of a metal top upon which the molten metal is adapted to impinge during 35 the pouring of an ingot, and a non-metallic body engaged with and attached to the underside of said top and which is of a material that will char and become friable under the intense heat, leaving a residue in the nature of charcoal. A material suitable for the purpose is a mixture of sawdust and an appropriate binder, such as a proper kind of glue or other substance that will evaporate when subjected to high temperature. The advantage of such a compound lies in the 40 fact that when an ingot, with the composite plug adhering to the bottom thereof as usual, is lowered into a soaking pit pursuant to common practice, the charred body portion of the plug will disintegrate and the particles thereof mingle with the coke customarily present in the bottom of the soaking pit as a conformable support for the ingot. As a consequence of the similarity of the material of the plug body and the coke bed, the so-called "sloppy bottom" condition of the pit, resulting from mixing refractory material with

the coke, is avoided and much difficulty and annoyance in frequent cleaning of the pit and ingots necessitated by such condition is obviated.

The purpose aforesaid is attained in the embodiments of the invention illustrated in the accompanying drawing wherein Fig. 1 is a perspective view, and Fig. 2 a central vertical section, through a mold plug constructed in accordance with the invention; Fig. 3 is a central vertical section through the lower portion of an ingot mold showing my improved plug in place within the bottom opening thereof, and indicating, in dot-and-dash lines, an implement or hook by which the plug is lowered into place; Figs. 4, 5 and 6 are central vertical sections through plugs constructed in accordance with the invention and incorporating, respectively, a different kind of combined handling and anchorage means; Fig. 7 is a similar view through a plug in which the top and bottom castings are connected together by anchorage means consisting of inexpensive and commonplace articles such as bent wires and nails, the handling means being dispensed with in this instance; and Fig. 8 is illustrative of one way of fabricating the plug. 25

In each of the several forms of the invention shown in the drawing, the metal top, or metallic top casting, is designated 1, and the non-metallic bottom casting is designated 2. While I have previously set out herein the desirability 30 of a material for the non-metallic bottom casting that would char and become friable under intense heat, and have specified a mixture of sawdust and a suitable volatile binder as one compound adapted to the purpose, it will be understood that various ingredients may be combined in the production of the non-metallic casting, many well known non-mineral materials and binders being suitable. 35

The anchorage means by which the two castings are connected together is designated, generally, by the numeral 3. In the form of the invention illustrated in Fig. 7, the anchorage means 3 may consist of nails or pieces of wire or the like, desirably bent so as to enhance their hold in the castings. In the other forms of the invention herein illustrated, handling means through which the plugs may be supported by a suitable implement or hook, is constituted of a part of the anchorage means. 50

In the embodiment illustrated in Figs. 1 to 3, the handling means a is constituted of the central portion of an inverted U-shaped rod or wire that forms the anchorage element 3. The ends 55 of the element are embedded within the non-

metallic casting 2 and are shown as upset to provide abutments or heads b.

In Fig. 4, the anchorage means 3 is in the form of a split or open sided ring whose central portion constitutes the handling means a, and whose ends are embedded in the non-metallic casting. In Fig. 5, the anchorage means 3, including the handling means a, is in the form of a staple constructed of a piece of wire or rod 10 of suitable diameter whose ends are turned inwardly at c to provide abutments that enhance the hold of the anchorage means within the non-metallic body. In Fig. 6, the anchorage means 3 consists of a double ended hook, desirably S-shaped, one end of which, designated d, is embedded in the non-metallic casting, while the opposite end provides the handling means a.

The method of producing the plug contemplates, broadly, preforming one casting with the anchorage means partly embedded therein and projecting from the side thereof to which the other casting is to be applied; and then applying to such side the material of the other casting while in mobile condition. In accordance with the present preferred method, the non-metallic casting 2 is molded with the lower portion of the anchorage means 3 embedded therein and with the upper portion of said means projecting well above the top surface thereof. The casting may be formed in a cavity 5 of a mold 6, conventionally illustrated in Fig. 8, or such casting, previously molded, may be placed within the cavity. Molten metal is then poured 35 upon the non-metallic casting, in some such manner as that illustrated in Fig. 8, to provide the casting 1 within which is encased the protruding portion or portions of the anchorage means. In the forms of the invention incorporating the handling means a, the appropriately shaped upper ends of the anchorage means extend well above the top surface of the casting 1.

By engaging the hooked lower end of an implement 8, shown in dot-and-dash lines in Fig. 3, with the handling means a, which, in the forms shown, is in the nature of an eye, the plug may, by means of said implement, be very conveniently lowered into the bottom opening O of the mold M, Fig. 3. The fact that the handling means is substantially central of the plug in-

sures proper entrance of the plug into the opening.

Notwithstanding the cheapness and simplicity of my improved mold plug, it is highly efficient as a closure for the bottom opening of the ingot mold because of the accuracy of its size and shape and freedom from burrs due to the method of production, it being understood that the mold cavities in which the castings are poured or formed correspond in size and shape to the bottom openings of ingot molds wherewith the plugs are intended for use.

Having thus described my invention, what I claim is:

1. A plug for the downwardly convergent bottom opening of an ingot mold, the same being of a size and shape to fit within and close said opening and comprising a metallic element that constitutes the upper portion of the plug and against the top side of which the molten metal 20 is adapted to impinge in the pouring of an ingot, and a solid, non-mineral body that constitutes the lower portion of the plug and is connected to the bottom side of said metallic element, the material of said body being such as will char 25 and become friable under intense heat.

2. A plug for the downwardly convergent bottom opening of an ingot mold, the same being of a size and shape to fit within and close said opening and comprising a metallic element that 30 constitutes the upper portion of the plug and against the top side of which the molten metal is adapted to impinge in the pouring of an ingot, and a body that constitutes the lower portion of the plug and is of cellulosic material, 35 the same being connected to the under side of said metallic element.

3. A plug for the downwardly convergent bottom opening of an ingot mold, the same being of a size and shape to fit within and close 40 said opening and comprising a metallic element that constitutes the upper portion of the plug and against the top side of which the molten metal is adapted to impinge in the pouring of an ingot, and a body that constitutes the lower portion of the plug and is attached to the bottom side of the metallic casting, the same being composed of wood sawdust and a suitable volatile binder.

HOWARD K. RIGDON. 50
